PACKING OR SHIPPING CASE

Karl F. W. Kempf, Buffalo, N. Y.

Application August 31, 1929. Serial No. 389,778

4 Claims. (Cl. 217—12)

My invention relates to improvements in packing or shipping cases.

Packing or shipping cases as now constructed cannot be conveniently used to reship goods.

5 This is oftentimes found desirable, particularly when goods are received which are intended to be distributed to branch houses, either in the quantities received, or in smaller quantities in connection with other goods packed in the same 10 case. Many concerns receive goods of various kinds from manufacturers and reship such goods to branches, distributors, or dealers in smaller quantities. A case having been received with a definite quantity of a particular kind or type of 15 goods can be partially emptied and other goods packed in the case to replace the goods removed, and the case so filled reshipped; but either a new cover will be found necessary to make the case suitable for shipment, or, where a case has a 20 hinged or other movable cover fastened to the body of the case by securing or tying devices, such as metallic bands, wires, or the like, new bands or wires must be provided, and nails, staples, or like fastening devices driven into the 25 walls of the case to secure the new bands or wires in place. Such new bands or wires have to be placed adjacent the old, since the original securing or tying bands or wires of the case were placed at points along the case which would 30 assure greatest security and protection for the goods encased and withstand the rough treatment the case would be subjected to in transit.

A packing or shipping case of a kind in common use comprises end, bottom and side walls 35 nailed or otherwise secured together, and a movable cover connected at one edge to the upper edge of one of the side walls by means of securing or tying wires fastened to the outer side of the cover, bottom, and side walls; opposite 40 ends of the wires being free and extending, respectively, beyond the free edge of the cover and the edge of the opposite side wall. When a case so constructed is filled and the cover lowered in position, the free ends of said wires are twisted 45 together to secure the cover in closed position; the encompassing wires otherwise serving to strengthen the walls of the case. When a case of this kind is received, it is necessary to shear or clip the wires adjacent the twisted ends in 50 order to gain access to the interior of the case; which renders them unfit for further use. Encompassing wires of this kind are usually fastened to the walls of the cases with staples, and since the cases are invariably constructed of hard wood, 55 it is a difficult matter to remove the staples.

Furthermore, owing to the number of staples used, it would be a tedious and expensive process.

In packing or shipping cases of this kind, the wires are always arranged at the ends of the case and one or more spaced between the end 60 wires; this being found necessary to prevent collapse of the case during shipment, especially when large numbers of metallic objects are shipped in the case.

The primary object of my invention is the 65 provision, in a packing or shipping case of the kind mentioned, of encompassing securing elements having means at their ends enabling the case to be used a number of times without the addition of new securing elements or parts. 70

Another object of my invention is the provision of encompassing securing strands having a plurality of free ends adapted to be twisted together in pairs in succession for shipment and reshipment. 75

A still further object is to provide encompassing wires at spaced intervals along the case, said wires being used in pairs and being fastened with staples along their lengths to the walls of the case, each staple serving to fasten the two wires of each 80 pair to said walls; opposite ends of one wire being adapted to be twisted together after the ends of the other have been twisted together for shipment and after shipment have been sheared or otherwise severed from the secured portions of the 85 wires.

With the above and other objects in view to appear hereinafter, my invention consists in the novel features of construction and in the arrangement and combination of parts to be hereinafter 90 described and more particularly pointed out in the subjoined claims.

In the drawing,—

Fig. 1 is a perspective view of a shipping case, having my invention applied thereto in one of the 95 many ways in which it may be used.

Fig. 2 is a front elevation of the case.

Fig. 3 is an enlarged cross section, taken on line 3—3, Fig. 4.

Fig. 4 is a detached perspective view of one of 100 the encompassing wires as it appears on the case after initial shipment and preparatory to reshipping the case.

My invention is shown applied to a "knock-down" shipping case now in common use; but it 105 may be used on any other kind of case in which the encompassing securing or reinforcing wires would or could serve as a hinge for one of the walls of a case.

The particular type of case shown in the draw- 110

ing has the top or cover, the sides or front and rear walls, and the bottom wall flexibly connected so that one can be folded over another and the end walls, which are originally separate, placed 5 between certain of the flexibly connected walls when folded, or placed upon the folded or overlying flexibly-connected walls. Boxes so constructed are shipped in knock-down form to the original user, and when received are unfolded so 10 that the flexibly-connected walls are positioned at a right-angle, one with respect to another, or others; the end walls are then inserted between the front and rear walls and over the bottom, resting with three of their edges against said 15 walls, to which they are nailed or otherwise secured so as to rigidly connect said walls and leave only the top as a flexibly connected wall, which serves as a cover for the case.

These several walls are flexibly connected with 20 wires which have their opposite ends free and extending, respectively, beyond the upper edge of the front wall and the free edge of the cover.

While my invention is particularly adapted for a "knock-down" case of this kind, it may be used 25 on any case having a wall loosely or movably arranged so access may be had to the interior of the case.

Referring now to the drawing in detail, 5 designates the end walls of the case, 6 and 7 the side 30 walls, or what may be termed the front and rear walls, respectively, 8 the bottom wall, and 9 the top wall or cover.

With the exception of the top wall or cover, these walls are rigidly secured together, and in 35 the preferred form of my invention, illustrated in the drawing, a plurality of pairs of encompassing or surrounding securing or tying wires are fastened to all the walls of the case so one wire of each pair lies in contact with the other.

40 The wires of each pair, are designated 10 and 11, respectively, and at spaced intervals, regularly or irregularly, they are fastened to the outer sides of all the walls of the case by staples 12, each staple embracing both wires.

45 While the front and rear walls are rigidly fastened together by means of the end walls, the encompassing wires reinforce and prevent collapse of these walls under the hard usage to which the case is subjected in transit, and these wires serve 50 to flexibly connect the rear edge of the cover to the upper edge of the rear wall, as at 13; the wires, at these points, functioning in a manner approaching the action of hinges so that the cover may be swung upwardly or downwardly over the 55 open upper end of the body portion of the case.

As stated, these wires are fastened to the outer 60 sides of all the walls of the case and they therefore extend across the cover. The wires are of a length so that opposite ends thereof extend beyond the upper front corner of the case when the cover is swung down into closed position. Otherwise expressed, one end of each wire extends in a free or loose manner outwardly beyond the front edge of the cover and the other end in a similar manner upwardly beyond the upper edge of the 65 front wall of the case.

In shipping cases in which encompassing securing elements are depended upon for protection and strength, one such element is arranged as 70 close as possible to each end of the case, and one or more, depending on the length of the case, between such end securing elements.

After packing a case provided with such encompassing elements, according to my invention, the 75 cover is lowered to close the upper open end of

the case and the loose or free ends of one wire of each pair are thrust into the case between the front edge of the cover and the upper edge of the front wall of the case, as shown at 14, while the ends of the other wire of each pair are firmly twisted together to secure the cover 80 tightly against the body portion of the case, and thence bent against the case, as shown at 15.

The unused and untwisted ends of the wires are therefore concealed and protected so that 85 they will not be broken away; moreover, they add no projecting parts to the securing element.

When a case so shipped is received, the contents may be removed in whole or part after shearing, snipping, or otherwise severing the 90 twisted portions of the wires.

When it is desired to reship the case after packing or repacking the same, it is simply necessary to twist the two unused ends together of the other wire of each pair; after which the ends of the wires of each pair will appear as shown at 95 16, Fig. 4. The case will be fully as secure for reshipment, as it was during its first shipment.

It is apparent, that the wires first used, but unused during reshipment, have no projecting parts 100 when the ends of the other wires are twisted together, preparatory to reshipping the case.

It will also be apparent, that if the case is intended for a number of reshipments, three or more wires can be assembled in the manner described to form each encompassing securing element, and each of the staples used will embrace 105 all the wires of each securing element.

While I have shown staples to fasten the bands or wires in place, other fastening devices 110 suitable for the purpose may be used.

Having thus described my invention, what I claim is:—

1. Securing means for a shipping case, comprising two wires encircling said case with free 115 ends adapted to be successively twisted together for locking said case, the ends of one of said wires being adapted to be twisted for the initial shipment of the case and to be clipped beyond the twisted portions thereof for opening said case, 120 and the ends of the other wire being adapted to be twisted together after clipping said first-mentioned ends for reshipment of the case, and staples encompassing said wires and driven into the case, each staple being common to both wires 125 and both wires serving to firmly secure the individual elements of the case together.

2. Securing means for a shipping case, comprising wires arranged in pairs and spaced apart, each 130 pair of wires encompassing the case with free ends adapted to be successively twisted together for locking said case, the ends of one wire of each pair being adapted to be twisted for the initial shipment of the case and to be clipped beyond the twisted portions thereof for opening said case 135 and the ends of the other wire being adapted to be twisted together after clipping said first-mentioned ends for re-shipment of the case, staples encompassing each pair of said wires and driven into the case, each staple being common to both 140 wires of each pair and both wires serving to firmly secure the individual elements of the case together.

3. Securing means for a shipping case, comprising two wires encircling said case, the ends of one of said wires being twisted together and the ends of the other wire being inserted through an opening in said case, said twisted ends being adapted to be clipped away for opening said case 145 and the inserted ends of said wires being adapted 150

to be twisted together for re-shipping said case, said cover at one edge thereof to the body portion of the case and to connect the individual elements of the body portion and said cover securely together, said wires having free ends extending beyond the opposite edge of said cover and adapted to be successively twisted for shipment and re-shipment of the case. 80

4. A shipping case having a cover and a plurality of pairs of wires surrounding the body portion of said case and extending transversely across said cover, said wires serving to flexibly connect
